(57) **CLAIM**

The ornamental design for an illumination source, as shown and described.

DESCRIPTION

FIG. 1 is a perspective view of an illumination source, showing my new design;

FIG. 2 is a front elevational view thereof;

FIG. 3 is a side elevational view thereof, the opposite side being a mirror image thereof;

FIG. 4 is a rear elevational view thereof;

FIG. 5 is a top elevational view thereof; and,

FIG. 6 is a bottom elevational view thereof.

The broken line showings in the Figures are for environmental purposes only and form no part of the claimed design.

1 Claim, 3 Drawing Sheets

FIG. 2

FIG. 4

FIG. 3
